BY
Howard E. Thompson
ATTORNEY

UNITED STATES PATENT OFFICE

JOHN J. WELSHOFER, OF NEW YORK, N. Y.

SHEET-METAL DOORFRAME CONSTRUCTION

Original application filed June 22, 1926, Serial No. 117,679. Divided and this application filed May 2, 1927,
Serial No. 188,274. Renewed April 5, 1930.

This invention relates to the latch plates for locks of various kinds and classes and particularly to devices of this class mounted in and constituting part of the door frame construction and in connection with which the latch bolt of a lock mounted on a door is adapted to operate; and the object of the invention is to provide a latch plate with means for quickly attaching the same to the door frame and supporting the same in an aperture in said door frame in such manner as to come in alinement with the latch bolt of a lock mounted on the door hingedly supported in said door frame, the mounting of said latch bolt being such as to permit of the quick attachment and detachment thereof, at will, and further to permit of its adjustment or reversing of the position thereof in the door frame to compensate for varying heights of the latch bolt on the door to bring the latch bolt receiving aperture of said plate in proper alinement with the bolt of the door; a further object being to provide a latch device of the class specified which is primarily adapted for use in sheet metal door frames, the door frame being fashioned to seat said plate with the outer face thereof flush with the outer face of the adjacent walls of the door frame, said plate having a movable device or devices adapted to engage the door frame to retain the same against accidental displacement; a further object being to provide a latch plate, which by virtue of its construction and use will permit of the construction of standard sheet metal door frames for supply to the trade as stock frames in stock sizes with a universal adaptation of a latch plate to said standard stock sized door frames, eliminating the necessity of constructing door frames specially for each individual building construction at the time of giving contracts therefor as is the usual custom, said standard frames being provided with an aperture of universal common form and dimensions to permit of the mounting of suitable latch plates in connection therewith; and with these and other objects in view, the invention consists in a device of the class and for the purpose specified, which is simple in construction and op-

eration, efficient in use, and which is constructed as hereinafter described and claimed.

This invention constitutes divisional subject-matter of my prior application filed June 22, 1926, Serial No. 117,679, and is fully disclosed in the following specification, of which the accompanying drawing forms a part, in which the separate parts of my improvement are designated by suitable reference characters in each of the views, and in which:—

Fig. 1 is a perspective view of a part of a door frame showing one of my improved latch plates mounted in connection therewith.

Fig. 1^a is a view similar to Fig. 1 but showing the latch plate mounted in a reverse position.

Fig. 2 is a partial section on the line 2—2 of Fig. 1 and on an enlarged scale.

Fig. 3 is a back view of the latch plate detached and indicating the manner of its mounting in a door frame.

Fig. 4 is a view similar to Fig. 2 but showing a modification; and,

Fig. 5 is a view similar to Fig. 4 but showing another modification.

In Fig. 1 of the drawing, I have shown for the purpose of illustrating one method of carrying my invention into effect a part of a sheet metal door frame 10 which may be of any conventional cross sectional form 11 representing the door stop portion of the frame, limiting the swinging movement of the door in one direction, which forms at one side thereof, a face 12 to receive the free outer face or edge of the door hingedly supported in the frame in the usual manner. The face 12 of the frame 10 at a predetermined distance above the floor is provided with an aperture 13 preferably elongated and rectangular in form to receive a latch or striking plate 14.

The plate 14 in the construction shown is provided with one elongated latch bolt receiving aperture 15 which extends closer to one end 16 of the plate 12 than the other end 17 thereof whereby the height of said aperture 14 in the door frame 10 may be raised

and lowered, the same being lowered in Fig. 1 and raised in Fig. 1^a. The upper and lower ends of said plate 14 are beveled inwardly to seat in corresponding outwardly beveled 5 ends in the aperture 13 of the door frame 10 as seen at 18, Fig. 2 of the drawing, whereby the plate 14 may be supported in the frame 10 with its outer face flush with the outer face of the bar 12 of the frame as clearly 10 seen in said figure.

The end 16 of the plate 14 is provided on its rear side with a strip 19 secured thereto in any desired manner, the edge 20 of said strip projecting beyond the beveled end of the 15 plate 14 to engage the inner face of the part 12 of the frame to retain the plate 14 or the end portion 16 thereof against displacement, while a lock or catch device 21 is pivoted to the other end 17 of the plate 14 as seen at 22 20 and adapted to extend onto the inner face of the part 12 of the frame 10 within the aperture 13 to secure the end 17 of the plate 14 against displacement. The member 21 may be moved from the position shown in dotted 25 lines in Fig. 3 of the drawing to that shown in full lines in Fig. 3 and also in Fig. 2 of the drawing, by a suitable tool passed inwardly through the aperture 15 in the plate 14.

In placing the plate 14 in position in the 30 aperture 13 of the frame, it will be understood that the end portion 16 is first inserted into the aperture 13 adjacent one end thereof, after which the other end 17 of the plate 14 is swung into position with the member 21 35 in the dotted line position shown in Fig. 3 of the drawing, and said member is then turned into the position shown in full lines as above stated.

In Fig. 4 of the drawing, I have shown a 40 modification wherein the part 12^a of a door frame, instead of being provided with the beveled faces as at 18 in Fig. 2 of the drawing, is offset to form stops 23 and 24 to limit the inward movement of a latch plate 25 and to 45 support the latch plate flush with the outer face of the part 12^a as clearly seen in Fig. 4 of the drawing, the inner face of the latch plate 25 being provided adjacent the ends 26 and 27 thereof with spring clips 28 adapted 50 to be sprung over the stops 23 and 24 and to engage the same as seen in Fig. 4 to secure the plate 25 against accidental displacement and yet permitting of the forcible removal of 55 said plate at will. The aperture 29 in the plate 25 is arranged in the same manner as the aperture 15 in the plate 14 whereby the plate may be reversed in the door frame to raise or lower the aperture 29. In the above 60 operation of attaching and detaching the plate 25, it will be understood that the spring clips 28 are sprung inwardly, and the rounded ends of said clips facilitate this operation.

In Fig. 5 of the drawing, I have shown an 65 other modification which incorporates part

of the principles seen in Figs. 1 to 3 inclusive and part of that shown in Fig. 4 of the drawing. In this construction, the attaching plate 30 is fashioned at one end to form a V-shaped notch 31 having a projecting inner flange 32 to engage the inner wall of the door frame, the V-shaped notch engaging a beveled face in the aperture of the door frame as seen in Fig. 2 of the drawing, while the other end of the plate 30 is provided on its inner end with a spring 33 adapted to engage a stop member 34 on the door frame as in the construction shown in Fig. 4. With this form of construction, the aperture 35 in the plate 30 will be centralized in that the plate 30 cannot be reversed in the door frame in the manner of the reversal of the plates 14 and 25. It will be understood, however, that either the upper or lower end of the plate may be provided with the spring clip 33 as may be desired, the door frame being fashioned to suit the construction employed.

It will also be understood that my invention is not limited to the specific means herein shown and described for detachably supporting the latch plate in connection with the door frame, nor to the specific form of said plate and various other changes in and modifications of the construction herein shown and described may be made, within the scope of the appended claims, without departing from the spirit of my invention or sacrificing its advantages.

Having fully described my invention, what I claim as new and desire to secure by Letters Patent, is:—

1. A sheet metal door frame fashioned to standardize the manufacture thereof, one of the side rails of said door frame being provided with a latch plate aperture and a latch plate mounted directly in connection with said door frame and fitting snugly in the aperture in the side rail thereof, and means for directly mounting the plate in connection with said frame in two different positions of the plate in the frame.

2. A sheet metal door frame fashioned to standardize the manufacture thereof, one of the side rails of said door frame being provided with a latch plate aperture and a latch plate mounted directly in connection with said door frame and fitting snugly in the aperture in the side rail thereof, means for directly mounting the plate in connection with said frame in two different positions of the plate in the frame, and opposite walls of said aperture being beveled outwardly to form seats for correspondingly beveled edges on said latch plate.

In testimony that I claim the foregoing as my invention I have signed my name this 29th day of April, 1927.

JOHN J. WELSHOFER.
